JACQUARD MACHINES

Cyril T. Dracup, Holly Bank, Holly Bank Road, Great Horton, and George Dracup, 1 Baslow Grove, Toller Lane, both of Bradford, Yorkshire, England

Filed Feb. 10, 1955, Ser. No. 487,390

5 Claims. (Cl. 139—63)

This invention relates to Jacquard machines and is particularly applicable to double cylinder Jacquard machines.

It is sometimes desired to arrange the pattern cards of a Jacquard machine so that a particular warp thread will remain in the up position for two or more picks of the loom. Such an arrangement is known as "semi-open shed" weaving. This is achieved by providing each warp thread hook with two catches or hooked pieces at the top, one catch facing each side of the machine. As the griff on one side of such a hook rises it carries with it the hook to a top position. As this griff descends it allows the hook to fall, but for semi open shed weaving the griff on other side of the hook which is then ascending is arranged to engage the other catch and lift the hook back to the top position. The pattern cards are so arranged that the griffs continue to lift the hook to the upper position at each pick so long as an open shed is required.

A disadvantage of such an arrangement is that at each pick the hook descends half way and is then caught by the other griffs; this results in a loss of power and wearing of the catches, harness threads and warp threads, due to the ascending griff checking the fall of the hook. It is an object of this invention to prevent this objectionable action.

According to this invention a Jacquard machine is provided with additional bars arranged to lie between the rows of hooks and to be moved during the operation of the machine so that for one pick they engage the hooks in one row, and then on the next pick they engage the hooks in the other row. By this arrangement it is possible to retain a hook in the upper position for any required number of picks, the hook being continually either on its griff or the additional bar.

The hooks may be provided with additional catches the additional bars being adapted to engage the additional catches when the griffs carry the hooks to the top of their movement.

The movement of the additional bars is preferably controlled by the Jacquard driving mechanism, and the bars are preferably carried in slots formed in fixed end plates and are rocked from one side to the other by means of movable plates which engage the bars and which are operated by suitable connections with the cylinder mechanism.

Alternatively the bars may be mounted on plates which are adapted to slide with a reciprocating motion so that they engage the hooks in one row and on the next pick the hooks in the other row.

In a still further alternative the bars may be pivoted about a longitudinal axis and formed with hooked or projecting pieces on each side which are adapted to engage the catches on the hooks.

The reciprocating rocking or sliding action can be transmitted to the bars by means of a cam mounted on a shaft driven by the jacquard driving mechanism.

2

The invention will now be particularly described with reference to the accompanying drawings in which:

Fig. 1 is a sectional view of a jacquard mechanism.

Fig. 2 is a view similar to Fig. 1 showing part of the jacquard mechanism in an alternative construction.

Fig. 3 is a detail sectional view of part of the mechanism shown in Fig. 2 in one position.

Fig. 4 is a sectional view of the same part shown in Fig. 3 after a pick has taken place.

10 Fig. 5 is a detail sectional view of an alternative form of additional bar.

Figs. 6A, 6B, 6C, 6D and 6E are sectional views showing respectively the position of one hook with its associated griff bars and additional bars in various positions after each of five succeeding picks.

Fig. 1 shows the general arrangement of the jacquard mechanism, the frame 1 has two arms 3 pivoted to the upper supports 5 and these arms 3 carry at their lower ends a plate 7. The plate 7 is duplicated at the other end of the machine (not shown) and the two plates carry between them a series of additional bars 9, which in Fig. 1 are shown having a V-shaped cross section but which may be of varyingly shaped cross sections as will be hereinafter described.

20 25 The plate 7 at one end of the machine is provided with a projection 11 adapted to engage the forked end 13 of a two armed lever 15 which is pivoted to the frame 1 at 17 and at its lower end has a cam follower 19 which engages a cam 21 on a shaft 23 which is geared to the jacquard driving mechanism. Thus rotation of the cam 21 is adapted to swing the lever 15 and thereby cause a reciprocating swinging motion to be transmitted to the plate 7 and thereby to the additional bars 9.

The jacquard is provided with the usual hooks 25 30 of substantially elongated U shape which at their lower ends are adapted to receive the warp threads or a connection to the warp threads, griffs 27 and 29, and needles 31. The vertical wires or stems 33 forming the hooks are adapted to be engaged by notches formed in the needles 31 in the usual manner to press the hooks out of line with the griffs 27 or 29 when required.

35 At their upper ends the two vertical wires 33 of each hook are each formed with two catches one above the other. The lower two catches 35 and 37 are adapted to be engaged by the griffs 27 and 29 in the usual manner. The upper catches 39 and 41 are adapted to engage the additional bars 9 as will be further described.

40 45 It will be understood that other parts of the mechanism are required but these are common to all double cylinder jacquard mechanisms and have been omitted for clarity, only the cylinder 43 and needle boards 45 being shown.

In the alternative construction shown in Figs. 2, 3 and 4 the additional bars 47 are flat plates and are carried in slots 49 in fixed plates 51.

50 55 The slots 49 are formed with inclined sides so that the tops are of sufficient width to allow the bars 47 to be rocked about their bottom edges, and to present the top edges alternately to the rows of hooks 25 on each side of each bar.

60 A movable plate 53 is also provided at one side of the machine and formed with slots 55 with the sides sloping toward each other at the top, and these slots are arranged to engage the bars 47 and to move them from one side of the slots 49 in the fixed plates 51 to the other.

65 70 The movable plate 53 is carried by two substantially vertical bars 54 pivoted at their upper ends to a part of the Jacquard framework. This will allow the movable plate 53 to oscillate in the desired manner. At one end the movable plate is provided with two cam followers 57 adapted to be engaged by a cam 59 driven from the Jacquard driving mechanism. The arrangement is such

that the cam 59 forces the plate 53 first in the one direction and then in the other.

In the alternative construction shown in Fig. 5 the additional bars 61 are fixed to a plate 63 adapted to move from side to side as described for the construction shown in Fig. 1 and to engage one or other of the hook catches 26.

In the arrangement shown in Figure 5 it will be noted that there is only one catch 26 on each hook stem, and that therefore the griff is arranged to lift the hook slightly above the catch on the bar 61 to allow the respective bar shift underneath it before the griff falls.

The operation of one hook will now be described to illustrate the operation of the machine with reference to Figs. 6A, 6B, 6C, 6D and 6E of the accompanying drawings and using the arrangement of additional bars shown in Fig. 2.

The griff 27 on the left hand side (Fig. 6A) engages the lower catch 35 on that side of the hook and raises the hook in the usual manner as shown at "A." At the upper end of its lift the top catches 39 and 41 are above the additional bars 47 and the bars are rocked by the movable plate so that the bar on the right hand side is in position under the catch 41 on that side (unless the appropriate needle is pressed by the cylinder) and the hook is thereby suspended as shown at B (Fig. 6B).

On the next pick the griff 29 on the right hand side lifts the catches 39 and 41 clear of the additional bars 47, which are then rocked over and the bar on the left hand side engages the upper catch 39 on that side (unless the appropriate needle is pressed by the cylinder card) as shown at C (Fig. 6C).

This process is repeated so long as it is desired to retain the particular warp thread at the upper position and it will be appreciated that the only movement given to the hook during this period is a slight lift to raise the catches clear of the bars for the bars to change over. When it is desired to lower a thread, the appropriate needle is pressed by the cylinder card and the upper catch thereby forced out of line with the bar as shown at D (Fig. 6D) so that the hook descends in the normal manner with the griff as shown at E (Fig. 6E).

This sequence of operations applies to any of the alternative constructions, except that in the case of the V-shaped additional bars 9 or the additional bar 61 shown in Fig. 5, no rocking action is necessary.

What we claim is:

1. A Jacquard machine comprising hooks mounted in rows, each hook comprising first and second vertical stems, each stem having a catch on its upper end, the catch on the first stem projecting in the opposite direction to the catch on the second stem, a first set of ordinary griff bars engageable with the catch on each first stem for raising said hooks, a second set of ordinary griff bars engageable with the catch on each second stem for raising said hooks, additional bars, and means mounting said additional bars above said ordinary griffs for move-

ment into and out of engageable relationship with said catches on said first and second stems alternately.

2. A Jacquard machine comprising hooks mounted in rows, each hook comprising first and second vertical stems, catches on said stems, said catches on said first stems projecting in the opposite direction to said catches on said second stems, ordinary griff bars engageable with said catches to cause lifting of said hooks, additional bars, and means mounting said additional bars above said ordinary griff bars for movement into and out of engageable relationship with said catches on said first and second stems alternately for holding said hooks in raised positions.

3. A Jacquard machine comprising hooks mounted in rows, each hook comprising first and second vertical stems, oppositely projecting catches on said first and second stems, ordinary griff bars engageable with said catches to cause lifting of said hooks, additional bars, and means mounting said additional bars above said ordinary griff bars for movement into alternative engageable relationship with the catches of the first and second stems respectively of hooks in adjacent rows, for holding said hooks in raised positions.

4. In a Jacquard machine, hooks mounted in rows, each hook comprising first and second vertical stems, oppositely projecting catches on said first and second stems, ordinary griff bars mounted for rising and falling movement and for engagement with said catches to cause lifting and lowering of said hooks, additional bars, and means mounting said additional bars above said ordinary griff bars for lateral reciprocating movement into alternative engagement with said catches on said first and second stems for supporting said hooks in raised positions.

5. In a Jacquard machine, ordinary griff bars mounted for rising and falling movement, hooks mounted in rows, each hook comprising first and second vertical stems, oppositely facing catches on said first and second stems, additional bars, a bar carrying said additional bars above said ordinary griff bars, cam means, and connecting means between said cam means on said bar to cause reciprocation of said bar to carry said additional bars into engagement with said catches of said first and second stems alternately for supporting said hooks in raised positions.
